UNITED STATES PATENT OFFICE

2,461,787

JEWELRY BOX

Samuel Trachtenberg, Cleveland, Ohio

Application October 26, 1945, Serial No. 624,731

1 Claim. (Cl. 206—44)

1

This invention relates to jewelry boxes.

An object of this invention is to provide a jewelry box comprising a base with a housing mounted thereon having a pair of hinged closure members and an article supporting means mounted on the base and adapted to be positioned inside the closures when the latter are in their closed position.

Another object of this invention is to provide a device of this kind which can be made out of metal, plastic or other suitable material, and which will form an attractive article for mounting on a dresser or table.

A further object of this invention is to provide a device of this kind which is adapted to releasably clamp a ring or the like, and is provided with means for receiving date cards to show the date of a wedding or other event.

It is the custom for a jeweler to use ring display boxes in his show window. These boxes are rather expensive and in the course of time, the velvet or other cloth covering surface used in connection with said boxes becomes faded, requiring the jeweler to either scrap the entire box or return it to a factory for recovering. The present invention enables the jeweler to readily himself remove and replace the covering material, thereby in the course of time, effecting a substantial saving.

It is also intended that the box of the present invention shall provide a permanent souvenir and attractive holder for use in the home, as by a bride.

With the foregoing object in view, and others which may hereinafter more fully appear the invention consists of the novel construction, combination and arrangement of parts, but it will be understood that changes, variations and modifications may be resorted to which fall within the scope of the invention, as claimed.

In the drawings:

Figure 1 is a top plan view of a jewelry box constructed according to an embodiment of this invention showing the box in open position.

Figure 2 is a detail front elevation of the device.

Figure 3 is a fragmentary sectional view of the ring clamping structure.

Figure 4 is a transverse section, partly in front elevation, of the rear portion of the ring supporting member.

Figure 5 is a perspective view of the box in closed position.

Figure 6 is a view, similar to Figure 3, showing the ring supporting means mounted on the base.

2

Figure 7 is a view, similar to Figure 6, showing a modified form of securing the ring support on the base.

Figure 8 is a perspective view of the ring supporting member removed from the housing.

Figure 9 is a perspective view of the box in open position.

Referring to the drawings the numeral 10 designates generally a base member which is formed with stepped or sloping marginal portions 11. The base 10 has rising therefrom a fixed housing, generally designated as 12. The housing 12 includes upright side walls 13, a double curved or humped top wall 14 similar to the top of a heart-shaped member and comprising two upwardly convex semi-circular portions joined at the depressed ends thereof or center of the top wall, and a rear wall 15. The housing 12 has hingedly secured to the forward edges of the side walls 13 thereof, a pair of closure members or doors, generally designated as 16 and 17, which are of like construction.

The closure members are formed of an outer side wall 18 which is hinged as at 19 to the forward edge of a stationary housing side wall 13. The side wall 18 has secured to the forward edge thereof, a front wall 20, and a fragmentary top wall 21 of substantially semi-circular configuration is formed integral with the side wall 18, and is secured to the front wall 20.

The lower ends 22 of the two closure top walls 21, are adapted to abut each other in line with the central depressed portion between the semi-circular portions of top wall 14 when the closures or doors are in closed position, and the inner edges of the front walls 20 are also adapted to be disposed in substantially abutting relation with the front walls 20 in alignment.

A knob 23 is secured to each front wall 20, and may be a jeweled knob or the like so as to provide an attractive appearance to the box when the closures are in closed position.

A ring supporting member, generally designated as 24, is disposed on the upper side of the base 10, and comprises a top wall or plate 25 formed with a forward, downwardly extending flange 26. The plate 25 has secured to or formed on the opposite lengthwise edges thereof downwardly extending flanges 27, and at the rear of the plate 25 there is mounted an upwardly extending box 28 which opens upwardly to form a top entrance slot and is provided in the forward wall 29 thereof with window openings 30.

A strip or card 31 is adapted to engage in the box 28 by passage through the top entrance slot.

with the dates thereof exposed through the windows 30. A substantially heart-shaped plate 32 is formed integral with the front wall 29 of the box 28, and the upper convex edges 33 thereof are adapted to loosely engage inwardly of or lie in spaced relation to the inner surfaces and meeting edges of the two semi-circular top wall members 14.

The plate 25 has, as shown in Figure 3, a lug 34, extending downwardly therefrom formed with a horizontally disposed threaded opening 35 within which a screw 36 disposed through the back or rear wall 15 of the housing 12 is adapted to be screwed and extended. The base 10, as shown in Figure 6, is formed with a transversely extending body 37 rising from the upper surface of the base adjacent the rear thereof, and through which the screw or bolt 36 loosely engages.

In the modification shown in Figure 7, the lug 34a is formed with a vertically disposed threaded opening 35a in which a vertically disposed bolt 36a is adapted to engage and in this instance the upper side 38 of the base 10a is flat from front to rear thereof. The plate 25 has a transversely extending slot 39 through which a pair of ring clamping jaws or plates 40 and 41 are adapted to loosely extend. The clamping plates 40 and 41 are pivotally mounted on a shaft or pin 42 extending between the depending sides 21, and are yieldably held in clamping position by means of a spring 43 mounted on the pin or shaft 42 to hold the plates or jaws 40 and 41 against a ring or the like.

I claim:

A display and souvenir box for rings and the like comprising in combination a base member, a housing secured thereto and a ring holding and indicia carrying platform removably connected with said housing and base member, the central upper part of said housing being substantially V-shaped and the forward half of said housing being formed of a pair of doors having front, top and side surfaces, said platform having at the rear thereof an upstanding indicia carrier, the central part of the upper surface of said carrier fitting within the said central upper part of said housing.

SAMUEL TRACHTENBERG.
